(57) **CLAIM**

The ornamental design for a double inseam access garment, as shown and described.

DESCRIPTION

FIG. 1 shows a perspective view of a double inseam access garment;

FIG. 2 shows a front view of the double inseam access garment;

FIG. 3 shows a rear view of the double inseam access garment;

FIG. 4 shows a right side view of the double inseam access garment;

FIG. 5 shows a left side view of the double inseam access garment;

FIG. 6 shows a top plan view of the double inseam access garment;

FIG. 7 shows a bottom plan view of the double inseam access garment;

FIG. 8 shows a perspective view of a double inseam access garment in an open position;

FIG. 9 shows a front view of the double inseam access garment in an open position;

FIG. 10 shows a rear view of the double inseam access garment in an open position;

FIG. 11 shows a right side view of the double inseam access garment in an open position;

FIG. 12 shows a left side view of the double inseam access garment in an open position;

FIG. 13 shows a top plan view of the double inseam access garment in an open position; and,

FIG. 14 shows a bottom plan view of the double inseam access garment in an open position.

The shade lines in the figures show contour and not surface ornamentation.

The broken lines shown in the figures show portions of the double inseam access garment which form no part of the claimed design.

1 Claim, 10 Drawing Sheets
